DESIGN FOR A STOCKING.

Application filed March 17, 1928. Serial No. 25,891. Term of patent 14 years.

To all whom it may concern:

Be it known that I, ALBERT STAUDTE, a citizen of the United States, residing at Philadelphia, county of Philadelphia, State of Pennsylvania, have invented a new, original, and ornamental Design for a Stocking, fully described and represented in the following specification and the accompanying drawing, forming part of the same, and showing a stocking embodying the design, the essential feature of which is the ornamental matter above the heel of the stocking, which is indi-

cated by cross hatching in contrast with the vertical lines which extend through the entire length of the stocking.

In said drawing Figure 1 is a rear view and Figure 2 a side view of the stocking embodying the design.

I claim:

The ornamental design for a stocking as shown and described.

In testimony whereof I have hereunto set my hand.

ALBERT STAUDTE.
